(57) **CLAIM**

The ornamental design for a hammer for a spreader apparatus, as shown and described.

DESCRIPTION

FIG. 1 is a front perspective view of a first embodiment of a hammer for a spreader apparatus;

FIG. 2 is a front elevational view thereof;

FIG. 3 is a rear elevational view thereof;

FIG. 4 is a right side elevational view thereof, the left side elevational view thereof being a mirror image of the right side elevational view;

FIG. 5 is a top plan view thereof; and,

FIG. 6 is a bottom plan view thereof.
